United States Patent Office

Des. 212,475
Patented Oct. 22, 1968

212,475

PASSENGER VEHICLE SERVICE UNIT

Terrence J. Mulligan, 2044B Best Place, Aurora, Ill., and
John K. Morrison, 618 S. 4th St., Aurora, Ill. 60505

Filed Sept. 1, 1967, Ser. No. 8,474

Term of patent 14 years

(Cl. D23—73)

Fig 3

Fig 4

Fig 5

FIGURE 1 is a perspective view of the front and one side of a passenger vehicle service unit embodying our new design.

FIGURE 2 is an elevational view taken from the right side thereof the opposite side being a mirror image thereof.

FIGURE 3 is a top plan view thereof.

FIGURE 4 is a front elevational view thereof.

FIGURE 5 is a rear elevational view thereof.

The dominant features reside in the portions shown in full lines.

We claim:

The ornamental design for a passenger vehicle service unit, as shown and described.
